SYSTEM FOR TRANSMITTING TELEGRAPH SIGNALS

Erich Hudec, Berlin, Germany

Application October 29, 1938, Serial No. 237,706
In Germany January 4, 1938

5 Claims. (Cl. 178—66)

This invention relates to telegraphy by pulses on electric waves and has for its principal object to compensate at the receiver any phase shift of the pulses received which may be caused by deviations between the synchronizing frequencies at the receiver and at the transmitter or by distortions on the way from the transmitter to the receiver or by any other distortions.

Another object of this invention is to provide means for shifting the phase of the receiver pulses in small steps to any degree beyond 360° or multiples of 360° .

Another object of this invention is to provide means for compensating the slightest phase shift between the pulses received from the transmitter and the pulses produced at the receiver, so that the variations of the telegraph signals will be very small.

Another object of this invention is to provide means for compensating also a large phase shift of the duration of a signal element.

It has been suggested to compensate fading and echo effects by transmitting merely the commencements or the ends of the telegraph signals by means of short pulses and to convert the pulses received into telegraph signals.

Furthermore it has been suggested to generate pulses at the receiver at equal intervals of time and to transmit only the missing pulses which are necessary for composing the telegraph signals at the receiver. It is to this system of telegraphy to which the present invention is particularly applicable. Such a system is described in detail in the copending application U. S. Serial No. 226,259, filed August 23, 1938, and comprises at the transmitting end a synchronizing frequency generator which controls a pulse generator for generating short periodic control pulses. This generator is preferably of the relaxation type. It is also provided with a motor driven distributor comprising a plurality of contacts connected to several teletype machines, as is conventional in multiplex telegraphy. The telegraph signals received from the teletype machines and the control pulses generated by the pulse generator are applied to a converter which generates a short telegraph or transmission pulse at the commencement or end of each telegraph signal, according to various schemes described in the co-pending application referred to above. The short telegraph pulses are transmitted and reconverted into telegraph signals at the receiving end of the system. The receiver is also provided with a synchronizing frequency generator which controls a pulse generator for generating short

periodic control pulses of the same periodicity as those generated at the receiver. These locally generated pulses, as well as the received telegraph pulses, are applied to a converter, preferably a relaxation device, by means of which the received telegraph pulses are converted into telegraph signals. These signals are then applied to several teletype machines in receiving position corresponding to those at the transmitting end, by means of a rotating distributor which is also controlled by the synchronizing frequency generator at the receiver. In this case the intervals between the fixed commencements (or ends) of the telegraph signals at the transmitter and at the receiver must coincide with extreme accuracy. In the case of picture telegraphy there is required a coincidence of at least 1.10^{-7} per cent of the transmission frequency.

According to the invention deviations between the fixed commencements or ends of the signals are compensated by shifting the phase of the locally generated receiver control pulses.

If e. g. the synchronisation frequencies at the transmitter and at the receiver differ from each other by more than 1.10^{-7} per cent of their value, but from their intended value by less than 1.10^{-7} per cent, the phase of the receiver control pulses is shifted at constant speed in such a manner that invariable telegraph signals are reproduced continuously in like fashion during the transmission.

The requisite rate of phase shift is determined in the most simple form with the aid of a few trial transmissions. If, for example, the synchronisation frequencies differ from each other by $0.5.10^{-5}$ per cent, it is necessary that the rate of the phase shift be adjusted with an accuracy of 1.10^{-3} per cent. By the use of a synchronous motor, which is driven by a frequency-regulated alternating current supply or better by a sub-harmonic of the synchronizing frequency, this accuracy can be realised and the deviation of the two synchronisation frequencies accordingly reduced to the amount of 1.10^{-7} per cent.

If the synchronisation frequencies at the transmitter and (or) the receiver do not remain constant with the requisite accuracy, the phase between the receiver and transmitter impulses must be frequently checked, and if necessary regulated.

For this purpose synchronizing pulses of predetermined constant duration and phase are transmitted from the transmitter to the receiver at certain predetermined intervals. The phase relation between the received synchronizing

pulses and the receiver control pulses must always be the same. If deviations from this predetermined relation occur, the phase of the receiver control pulses is shifted in accordance with the degree of these deviations.

In the accompanying drawings embodiments of the invention are illustrated diagrammatically.

Fig. 1 shows an arrangement for shifting the phase of the synchronisation frequency at the receiver.

In Fig. 2 there is explained the operation of the arrangement according to Fig. 1.

Fig. 3 shows the mechanical arrangement of the resistances R in Fig. 1.

Fig. 4 shows a device for controlling the phase shifter according to Fig. 1 by synchronizing pulses received from the transmitter and control pulses produced at the receiver.

Fig. 5 illustrates the operation of the devices according to Figs. 4 and 6.

Fig. 6 shows on the right side a device for producing the telegraph signals and on the left side a device for controlling the phase shifter according to Fig. 1 by synchronizing pulses received from the transmitter and control pulses produced at the receiver.

Fig. 7 is a diagram showing the distribution at the receiver of telegraph pulses received from the transmitter and control pulses produced at the receiver of the reproducing telegraph signals and illustrates the operation of the phase shifting arrangement of Fig. 8.

Fig. 8 shows a device for shifting the receiver control pulses in both directions according to the phase of the synchronizing pulses received from the transmitter.

Fig. 9 shows a complete arrangement at the transmitting and at the receiving side for carrying out the invention.

Means for producing telegraph pulses at the beginning or at the end or in the middle of a telegraph signal, means for producing local pulses at the receiving end for fixing either the termination or the commencement of the telegraph signals, and means for converting the pulses received into telegraph signals have been described in my corresponding application Ser. No. 226,259 filed Aug. 23, 1938, referred to above.

Fig. 9 schematically shows a complete system for transmitting and receiving telegraph signals in accordance with the present invention. For the purpose of clearness, all electrical connections between the units represented by the blocks 1 to 19 are indicated by single heavy lines.

At the transmitting end, there is provided a synchronizing frequency generator, preferably comprising a tuning fork generator capable of delivering electrical oscillations at 1,000 C. P. S. Connected to the generator 1 is a control frequency generator 2, tuned to a subharmonic of the synchronizing frequency and accurately synchronized therewith. The control frequency signal generated is used for controlling the motor driving a distributor 4, and for controlling a relaxation generator 3 which generates control pulses of relatively short duration, as compared with a telegraph signal unit or baud. The distributor 4 preferably comprises 32 contacts which are closed once during each revolution of the distributor spindle. 30 contacts are used for scanning the contacts of 6 tape transmitters (not shown) and 2 contacts are used for generating testing signals for synchronizing the receiving apparatus. The control pulses developed by the generator 3 are periodic and so spaced that one

pulse occurs during each cycle of the control frequency and also during each telegraph unit of the telegraph signals produced by means of the teletypers and the distributor 4. The control pulses and the telegraph signals derived from the contacts of the distributor 4 are applied to a transmission pulse generator 6 and more specifically to the control grid of a negatively biased electron discharge tube in such a manner that a telegraph or transmission pulse is generated in the plate circuit of the electron discharge tube whenever a marking unit of the telegraph signals to be transmitted occurs. During occurrence of a spacing unit in the telegraph signal, no transmission pulse or telegraph pulse is developed. During occurrence of a synchronizing signal, however, a synchronizing pulse is developed which is transmitted, together with the telegraph pulses, so that the transmission pulses comprise telegraph and synchronizing pulses. Wherever the distance between the telegraph station and the radio transmitter makes it desirable, a line carrier frequency generator 5 is provided, preferably generating a frequency which is harmonic of the synchronizing frequency developed by the generator 1. This intermediate carrier is modulated or keyed by the telegraph and synchronizing pulses and then transmitted by way of a wire line to the actual radio transmitter. At the transmitter, there is provided a demodulator 7 for demodulating the keyed intermediate carrier. The telegraph pulses and synchronizing pulses are then applied to the modulating stage of the radio transmitter 8 which transmits a carrier signal keyed or modulated in accordance with transmission pulses comprising telegraph and synchronizing pulses to be transmitted. At the receiving end there are provided two antennas, preferably directive, connected to two receivers 9 and 10. At the receivers, the received keyed carrier is demodulated and the demodulated transmission pulses are again modulated upon an intermediate carrier and supplied to an amplifier and demodulator 16. At the receiver there is also provided a synchronizing frequency generator 11, preferably comprising a tuning fork generator capable of developing electrical oscillations having a frequency of 1,000 C. P. S. The frequency of this generator can be adjusted within narrow limits by means of condensers and is adjusted to substantially the same frequency as that of the generator 1 at the transmitting end. The synchronizing frequency is applied to a phase shifter 12 in which the phase of the synchronizing frequency can be advanced or retarded, thereby to adjust the phase of the periodic receiver control pulses by the pulse generator 13. Adjustment of the phase of the synchronizing frequency is effected in such a manner that the phase of the receiver control pulses remains in predetermined constant phase relation with respect to the received synchronizing pulses. The receiver control pulses are preferably produced by means of a harmonic generator in the same way as the control pulses at the transmitting station. The generator 13 is tuned to a subharmonic of the synchronizing frequency generated by the generator 11 and is synchronized by the phase-adjusting synchronizing frequency, that is, the output of the phase shifter 12. The periodicity of the receiver control pulse is substantially the same as that of the control pulses generated at the transmitting end. The control pulses are

utilized for controlling the motor of the distributor 19 which distributes the reproduced telegraph signals to the various teletype machines. There are also provided two relaxation generators 14 and 15 for producing relatively short and relatively long receiver control pulses, respectively. The distributor 19 comprises 30 contacts for 6 teletype machines, 2 contacts for phase control and a glow lamp for testing the phase of the distributor.

The demodulated transmission pulses comprising telegraph and synchronizing pulses are applied to a converter 17 in which the pulses of relatively short duration are converted into signals having durations equal to telegraph units. For this purpose, the short receiver control pulses developed by the generator 14 are applied to the converter 17. The reproduced telegraph signals are applied to the teletype machines by means of the contacts of the distributor 19. For the purpose of comparing the phase of the received synchronizing pulses with that of the receiver control pulses, there is provided a phase comparator 18 to which received synchronizing pulses and receiver control pulses are applied. In the phase comparator 18, the phase of the leading edges of the received synchronizing pulses is compared with the phase of the leading edges of the short and long receiver control pulses. For proper phase relation, the short receiver control pulses must occur within the duration of the received synchronizing pulses and the latter must occur within the duration of the long receiver control pulse. Whenever short receiver control pulses are in advance of the received synchronizing pulses, the motor of the phase shifter 12 is energized to vary the constants of the phase shifter 12 so that the phase of the synchronizing frequency is shifted backwards. Whenever the received synchronizing pulses are in advance of the long receiver control pulses, the motor of the phase shifter 12 is controlled in the opposite sense.

An arrangement for carrying out the phase shift of the receiver control pulses is illustrated in Fig. 1. It consists of two independent phase shifters, by means of which the phase of the potential applied to the control grid of an electron discharge tube can be shifted by almost 180° in relation to the plate potential of the preceding tube.

The resistances R of each of the two phase shifters are coupled together, so that they always have the same values.

Fig. 2 illustrates the operation of the arrangement of Fig. 1. The potential in the current branches 1-3-2 or 5-7-6 is

$$U_1 = J \cdot R + \frac{J}{j\omega C}$$

and in the current branches 1-4-2 or 5-8-6

$$U_2 = \frac{J}{j\omega C} + J \cdot R$$

From this it follows that the points 3 and 4 or 7 and 8 in Fig. 2 move diametrically on a circle in the case of variable R . U_2 accordingly varies its phase in relation to U_1 without varying its amplitude.

The resistances R , in accordance with Fig. 3, are designed as rotary resistances and are rotated simultaneously. They commence simultaneously with the value W , vary step by step up to a maximum finite value, then jump to infinity, and then after a complete revolution sud-

denly return to R_0 . The phase angle ψ between the potentials U_1 and U_2 varies thereby in small stages from approximately 0° to 180° and then suddenly jumps back to approximately 0°. Accordingly the phase angle ϕ between the output potential U and the input potential U_0 increases from approximately 0° to 360° and then suddenly drops back to approximately 0°.

If the four resistances in Figs. 1 and 3 do not 10 pass simultaneously from the final contact segment to the first one, the phase of the output potential U can assume for a brief period the value of 180° or even drop in its amplitude to zero.

15 These distortions can be reduced by adjusting the contact segments in Fig. 3 very exactly one above the other; they cannot, however, be completely eliminated.

The remaining errors are eliminated according 20 to the invention by controlling by the output potential U a tube generator, a relaxation generator or a synchronous motor—arrangements which exhibit inertia in face of a variation in phase. Therefore the jump from 360° to 0° is not observable, so that if the phase shifter according to Figs. 1 and 3 rotates beyond 360° or any multiple of 360°, the phase of the receiver pulses will be shifted beyond 360° or any multiple of 360°.

25 In Fig. 3 there are shown by way of example switches having 21 steps. The distributor brushes for the switches are located on the same shaft and are driven by the motor M by way of an intermediate reduction gear (not shown). The resistances for the single steps are so calculated that the phase angle between the input potential U_0 and the output potential U in Fig. 1 varies from step to step by the same angle $\Delta\phi$. The angle ψ between the potentials U_1 and U_2 in Fig. 2 is determined by the equation

$$t \frac{\psi}{2} = R \omega C$$

The resistances R for the single steps should be selected according to this relation.

45 However, the phase angle between the input potential U_0 and the output potential U of the phase shifting device is of ultimate concern, rather than the phase angle between the potential U_1 and U_2 . The phase angle between U_0 and U for various values of R can be determined by means of a vector diagram with consideration of the vacuum tube impedances, the transformers, and the load resistors W .

50 The lowest value of the resistors R of Figs. 1 and 3 is equal to that of the resistors R_0 . At the second and following contacts of the switches in Fig. 3, the values of their resistors R increase until they become infinity at the twenty-first contact for $R = R_0$, the phase angle between U_0 and U is $K \times 360^\circ$; at the second contact, it is $K \times 360^\circ + 18^\circ$, and increases in steps of 80° from contact to contact.

55 If the steps $\Delta\phi$ by which the phase angle is varied are to be reduced, it is necessary to increase the number of segments of the rotating switch, but the required accuracy with which changes from contact to contact must be effected also increases, so that a practical limit for the number of contact signals is soon reached. The amount $\Delta\phi$ may also be decreased by shifting the phase of a higher harmonic of the frequency required and reducing it to the desired frequency by means of a vacuum tube frequency divider or a relaxation generator.

If the phase between the transmission pulses received and the receiver control pulses is shifting continuously in one direction, the phase shifter may be driven by a synchronous motor by means of a gear. This method may especially be used for the transmission of pictures as the stability of the synchronising frequencies which may be realised by means of a quartz crystal is just sufficient for the time needed for the transmission of one picture.

If the synchronising frequencies at the transmitter and at the receiver do not remain constant with the requisite accuracy, according to the invention testing pulses of predetermined constant wave shape and periodicity are transmitted at predetermined intervals, as explained below in detail.

In broad terms, it is a feature of the present invention periodically to generate synchronizing signals of constant wave shape and periodicity, preferably at the end of each revolution of the distributor arm of a multiplex system, to convert these synchronizing signals into synchronizing pulses with the aid of control pulses, in the same manner as the telegraph signals are converted into telegraph pulses, and to transmit the transmission pulses comprising telegraph and synchronizing pulses. At the receiving end of the system, control pulses are generated having substantially the same periodicity as those generated at the transmitter. The receiver control pulses are to be held in synchronism and in phase with the received telegraph and synchronizing pulses, which, if transmitted through the ether, may suffer phase distortion due to echo effects. The control pulses generated at the receiver are utilized to convert the received telegraph and synchronizing pulses into signals. In order to maintain phase identity between the control pulses locally generated at the receiver and the received transmission pulses, the phases of both are compared in a phase comparator device to produce a control effect which is utilized to adjust the phase of the receiver control pulses to a predetermined relation with respect to the phase of the received transmission pulses. If correction is to be effected for both a lead and lag in the phase of the receiver control pulses with respect to the received pulses, two types of receiver pulses are generated of equal periodicity but of different wave shape. Both these types of pulses are compared with the received pulses to produce control effects adapted to correct the lead and lag, respectively, of the receiver control pulses.

For distributing the received telegraph signals to the different telegraph receiving apparatus there are provided at the receiving end of a system operating in accordance with the multiplex method of telegraphy a plurality of telegraph signal contact segments, which are contacted successively by a distributor arm and contact brush. Generally there are provided for each receiving apparatus 5 segments corresponding to the 5 units of the telegraph code.

For compensating the error in synchronism there are required two synchronizing segments in addition to those telegraph signal contact segments. The arrangement is so adjusted that the distributor contact brush passes over the first of these synchronizing signal segments when, for example, a spacing interval in the telegraph signal is received, and it passes over the second synchronizing signal segment when a signal element is normally received. The rotation of the

distributor arm and the generation of the receiver control pulses are so tuned that a control pulse commences just at that moment at which the arm reaches a new contact segment. If the

5 received synchronizing pulses commencing at the same moment, there is produced a spacing or blank interval upon the contact of the distributor brush with the first signal segment of the distributor and a signal is produced upon the contact of the brush with the second signal segment.

If the phase of the received transmission pulses is leading in phase with regard to the receiver control pulses, the signal already commences when the distributor brush is still on the first

15 synchronizing signal segment. This part of the signal acts by way of the first synchronizing signal segment on the grid of the electronic valve

1 in Fig. 4 and causes the condenser C to become charged to an extent which is all the greater the

20 greater the phase shift is between the transmission pulses and the locally generated receiver control pulses. During the succeeding contact of the distributor brush with telegraph signal segments connected to the teletype receiver the

25 condenser controls the electronic valve 2, the plate current of which is used to actuate an electro-motor M. This motor varies the resistance R in Fig. 1, and accordingly shifts the phase of the synchronisation frequency at the receiver

30 which also determines the phase of the receiver control pulses. Shortly before the distributor arm of the multiplex apparatus moves on to the first synchronizing segment the condenser is discharged by way of a contact of the distributor

35 apparatus or, in accordance with Fig. 4, by way of a relaxation apparatus, which is made to be current-transmissive by a distributor contact schematically indicated at S. When the distributor arm again reaches the first synchronizing signal segment this occurrence is repeated, if the received transmission synchronizing pulses do not coincide with the receiver control pulses.

If the phase of the testing pulses received from the transmitter is lagging in regard to the receiver control pulses, the signal commences only during the wiping of the second synchronizing signal segment. This error can also be compensated by allowing the signal to act in a negative direction by way of the second synchronizing

50 signal segment on the grid of the electronic valve 1 in Fig. 4, which in this case is positively biased. The positive grid bias should be so great that the same is just compensated by the negative signal potential. If the signal by way of the

55 second synchronizing segment initiates too late, the positive bias is effective for a time, so that the condenser C is charged. Apart from this the operation is the same as in the first example. In this case the motor must rotate in the opposite direction.

If the phase of the received transmission pulses sometimes is leading and sometimes lagging, there are required two arrangements according to Fig. 4, the one of which is connected with the

65 first synchronizing signal segment and the other with the second synchronizing signal segment. There can be provided two arrangements according to Fig. 1, which are independent of each other, or the two motors M can act in opposite directions on the same resistances R in Fig. 1.

In the case of image telegraphy the same method can be employed, although in this case it may be difficult to close the synchronizing contacts exactly for the duration of one screen period. If the phase of the received transmission pulses

is leading, there are preferably produced at the receiver special synchronizing pulses, which are of longer duration and greater amplitude than the synchronizing pulses received from the transmitter, both pulses being superimposed in opposite polarity to one another during the synchronizing period. The testing pulses received from the transmitter are rendered completely ineffective by the receiver control pulses when they coincide. If on the other hand the synchronizing transmission pulses are in advance (compare Fig. 5a), they are effective for the time up to the commencement of the receiver control pulses. They are allowed to control a motor, the velocity of which is adjusted according to the degree of phase displacement. By this motor the resistances of a phase shifter (for example according to Fig. 1) are altered, and in this way there is corrected the phase of the testing receiver pulses relatively to the synchronizing pulses received from the transmitter.

In order to ensure that errors do not occur in the case of image telegraphy the synchronizing period at the transmitter is made to be greater than at the receiver, so that it is ensured that at the receiver only synchronizing pulses are received during the synchronizing period. This method can be carried out in a manner similar to that in the described example of multiplex telegraphy according to Fig. 4.

If, contrary to the last example, the phase of the synchronizing pulses received from the transmitter lags with respect to the phase of the receiver control pulses, the receiver control pulses are adjusted according to Fig. 5b. They are made of shorter duration and smaller amplitude than the synchronizing pulses, so that they are only effective when they lead the synchronizing pulses in phase. In this case, therefore, the electronic valve 1 in Fig. 4 is controlled by the receiver control pulses, and the latter are applied in opposite polarity with respect to received synchronizing pulses. The condenser C is charged exactly as in the previous example, but only when the received synchronizing pulses lag behind the control pulses. Apart from this the compensation occurs exactly as in the previous example.

Finally, it is also possible according to this method to compensate the errors in phase when the synchronizing pulses received from the transmitter alternately lead or lag behind the receiver control pulses. There are then required at the receiver two different control pulses, viz. according to Figs. 5a and 5b, and two arrangements according to Fig. 4. The phase of the receiver control pulses is advanced by means of one of these arrangements and retarded by the other.

The arrangement according to Fig. 4 operates faultlessly, but it has the disadvantage that a comparatively large shift must take place between the transmission and receiver impulses before the condenser has been sufficiently charged to control the motor.

This disadvantage is avoided in the arrangement according to Fig. 6 in which a very slight advance of the receiver pulses already causes a displacement of the phase shifter, so that there occur only very small differences in the duration of the telegraph signals reproduced at the receiver.

According to the invention this is accomplished by controlling, during the synchronizing period, a relaxation device in accordance with the receiver control pulses and transmitted synchronizing pulses, which are applied in opposite polarity and so adjusted that they have nearly the same ampli-

tude. The relaxation device is caused to relax, for example, by the receiver control pulses alone, whereas it is not affected by the transmitted synchronizing pulses. Shortly prior to the synchronizing period the relaxation device is caused to relax into the other position by means of a special contact, hence preparing it for reception of a receiver control pulse. This method is described in detail and illustrated in the following for a multiplex telegraph system.

At the transmitter and at the receiver there is provided a distributor having, for example, 31 segments, of which 6×5 segments are employed for the telegraph signals of 6 telegraph apparatus, while the thirty-first segment is used to transmit upon each revolution a synchronizing pulse, which corresponds in wave shape to the other telegraph pulses. It differs from these merely by the fact that it is always transmitted, whereas the telegraph pulses are transmitted or not transmitted dependent on the combination of the telegraph signal to be transmitted. The generation of the telegraph pulses is described in the patent application (Ser. No. 226,259 of Aug. 23, 1938).

At the receiver the transmission pulses comprising telegraph and testing pulses are preferably picked up by means of a plurality of aerials and a plurality of independent receiving sets and transmitted over separate wire lines to a telegram collecting office by means of an intermediate carrier frequency. The intermediate carrier is amplified and demodulated and the demodulated telegraph and testing pulses applied together to a limiting device, for example an electronic valve or a relaxation device, which is so sensitive that it can be fully or practically fully controlled by the pulses received from one receiver.

In Fig. 6 a device for producing the telegraph signals and the synchronisation signals according to the invention is illustrated by way of example. It is divided into its two parts by the thin broken line.

For reproducing the telegraph signals by means of the received telegraph pulses there is provided the grid-controlled relaxation device K_1 , which is connected in series relation with the resistance R_1 and to a source of unidirectional potential of preferably 50 volts. The control grid of K_1 is controlled by the transmitted telegraph and synchronizing pulses SI applied at terminals 8 and 9 and the receiver control pulses EI applied at terminals 10 and 11, which are produced at the commencement of each telegraph unit by the compensated receiver synchronisation frequency. The grid bias is so adjusted by means of the potentiometer W_1 that the upper relaxation potential $\bar{U}$ is above and the lower relaxation potential $\underline{U}$ below the plate potential U ($=50$ v.). By means of the receiver control pulses the two relaxation potentials are preferably increased, so that the relaxation device K_1 does not transmit current. Owing to the received telegraph and synchronizing pulses applied to the control grid of K_1 , the relaxation potentials are reduced, so that K_1 becomes conductive.

The printing apparatus at the receiver are preferably so connected that the receiving relays actuate the permutation bars when they are not excited by the telegraph signals, as in this way the operation of the relays can readily be checked, no signals being transmitted to the receiver. The device according to Fig. 6 is adapted

to this form of operation of the printing apparatus.

If, at the commencement of a telegraph unit, no transmission pulse is received, the relaxation device K_1 is rendered non-conductive by a receiver control pulse. Therefore there is no negative bias at the resistance R_1 , so that plate current flows in the plate circuit of the amplifying valve V_1 for the duration of the next telegraph unit. This plate current flows by way of the distributor connected to terminals 1 and 2 to one of the five receiving relays of a printing apparatus.

Since the received transmission pulses exceed the receiver control pulses in amplitude and duration (the resistances W_1 , W_3 and W_4 are adjusted accordingly) it is thus assured that the relaxation device becomes conductive when a telegraph pulse is received. Upon arrival of a telegraph pulse a negative voltage drop is developed across R_1 , by means of which the amplifying valve V_1 is blocked, so that the appertaining receiving relay remains unexcited and the permutation bar is actuated.

All remaining parts in Fig. 6 are intended for the regulation of the synchronism. The amplifying valve V_2 , which is connected in parallel with the valve V_1 , feeds a glow lamp, which is connected by way of a transformer $\bar{U}$ and the terminals 6 and 7 and lights a stroboscopic disc in the distributor. If no telegraph pulses are transmitted by the transmitter there is only transmitted a synchronizing pulse upon each revolution of the contact drum of the distributor, by way of the distributor contact 31 of Fig. 8, a synchronizing pulse is received at terminals 8 and 9 by means of which K_1 is rendered current-transmissive and V_2 is blocked. The pulse developed thereby in the transformer $\bar{U}$ causes the glow lamp to light and can accordingly be employed for phase adjustment.

The relaxation device K_2 and the amplifying valve V_3 are used for adjusting the phase of the receiver pulses. The grid of the relaxation device K_2 is normally supplied by way of a high-resistance R_4 with a negative bias, which is so adjusted that the plate voltage of 50 volts lies the lower relaxation potential U .

By means of a distributor contact, the terminals 3 and 5 are conductively connected. In this manner the received synchronizing pulses applied from the distributor synchronizing signal contacts to terminals 8 and 9 and the receiver control pulses applied at terminals 12 and 13 are applied to the control grid of the relaxation device K_2 by way of potentiometers W_5 and W_2 , and W_6 and W_2 , respectively. The potentiometers W_5 and W_6 are so adjusted that the transmission synchronizing pulses exceed the receiver control pulses in their amplitude and render the latter ineffective when they occur simultaneously. If, on the other hand, the receiver control pulses are somewhat in advance, the relaxation device K_2 is made non-conductive. Therefore, there is no negative bias at R_2 , so that a plate current flows in the valve V_3 and actuates the relay P . The relay P switches a motor on by way of the terminals 14 and 15, which actuates the phase shifter in accordance with Figs. 1 and 3 and brings the rotation of the distributor arm and the receiver control pulses again in phase with the received synchronizing pulses.

If the duration of the received testing pulse extends beyond the termination of the relatively short receiver control pulse, relaxation of the

device K_2 must not be caused thereby. For this reason, the grid bias of the relaxation device K_2 must be so adjusted by means of the potentiometer W_2 that the plate potential is considerably closer to the lower relaxation potential U than to the upper relaxation potential $\bar{U}$ of the device K_2 .

It is only approximately after one revolution of the drum, shortly before the contact 31 of Fig. 8 is closed, that the grid of the relaxation device K_2 is connected with a source of positive bias by way of a conductive connection between terminals 3 and 4 effected by a distributor contact and K_2 is rendered conductive. The amplifying valve V_3 and the relay P are thus deprived of current, and the motor M is disconnected. It remains stationary for such time until the receiver pulse is in advance of the transmission pulse and causes the relaxation device K_2 to become non-conductive.

When the synchronizing pulses received from the transmitter are leading the receiver control pulses in phase, receiver control pulses are employed, which are adjusted to be greater in amplitude and longer in duration than the synchronizing pulses received from the transmitter. As soon as the synchronizing pulses received from the transmitter are slightly ahead of the control pulses produced at the receiver, they control a phase shifter, by means of which the phase of the synchronization frequency at the receiver is shifted in the forward direction until the synchronizing pulses received from the transmitter are in phase with the receiver control pulses. The synchronizing pulses received from the transmitter then become ineffective, so that the phase shifter remains stationary.

This method fails, however, if the echo effects accidentally exceed the assumed maximum extent and the synchronizing pulses received from the transmitter become effective after the end of the corresponding receiver control pulses. The phase of the receiver pulses is then incorrectly shifted in the forward direction and the synchronism is disturbed.

This drawback is eliminated by superimposing the synchronizing pulses received from the transmitter and the receiver control pulses in opposite polarity by means of a special distributor testing contact, which limits the effective duration of the synchronizing pulses received from the transmitter.

In Figs. 7 and 8 this method is illustrated by way of example as applied to multiplex telegraphy wherein the phase of the receiver control pulses may be shifted in both directions.

In Fig. 7a there are shown the receiver control pulses EI , which are employed together with the received transmission pulses comprising telegraph and synchronizing pulses SI (Fig. 7b) for reproducing the telegraph signals TZ (Fig. 7c). In Fig. 7b it is assumed that duration of the received transmission pulses SI is extended up to 50% of the telegraph signal unit due to echo effects. The telegraph signals are distributed to the receiving relays of the telegraph printers by means of the receiver distributor EV . In Fig. 7d there are shown the distributor contacts 26 . . . 30, which lead to the teletype printer VI . There are actuated by the telegraph signal TZ of Fig. 7c, for example, the first, second and fifth receiving relays, while the third and fourth are in the stationary position. This combination represents the letter "W" in the international telegraph code.

According to Fig. 7d, the distributor contacts are closed only for one-half of the duration of a telegraph signal unit. If the received transmission pulses coincide in phase with the receiver control pulses, as illustrated in Figs. 7a-d, the time during which the distributor contacts are closed falls exactly in the middle of the telegraph signal unit. Since the receiver control pulses and the receiving distributor are controlled by the same synchronization frequency at the receiver, the mutual phase relation between the receiver control pulses EI and the closing of the distributor contacts EV always remains the same.

If the received transmission pulses are shifted in the forward direction, a signal unit of the reproduced telegraph signal released by a transmission pulse is not varied at all, as long as the receiver control pulse occurs within the duration of the transmission pulse. On the other hand a portion of a preceding spacing unit is changed into a telegraph marking signal shortly prior to the termination of the spacing unit. This short, faulty telegraph marking signal, with the assumed closing time of the distributor contacts, remains without effect as long as it is less than 25% of the duration of a normal signal unit. If it becomes longer, it can incorrectly actuate the receiving relay connected to the telegraph signal contact of the distributor preceding the synchronizing contact.

If the received transmission pulses shift backwards, a telegraph signal marking unit is correspondingly shortened in its duration below that of a normal signal unit. In the case of a shifting of 25%, however, the part of the signal unit acting on the receiving relay is not varied. But if the transmission pulses are lagging behind the receiver control pulses by more than 25% of the signal unit the duration of the reproduced telegraph signal may possibly no longer be sufficient to actuate the receiving relay.

In order that the permissible shifting of the received transmission pulses be as large as possible, the contact duration of the distributor contacts must be so chosen that it is just sufficient to permit actuation of the receiving relay. In order to shorten the permissible contact duration the receiving relays are preferably actuated by way of storage condensers.

After the final signal unit for the final telegraph printer (corresponding to contact 30 of Fig. 7) a pulse is omitted upon each revolution of the distributor at the transmitter and following thereon there is transmitted the synchronizing pulse which is designated P in Fig. 7b. This synchronizing pulse, in the same manner as the other transmission pulses, produces a telegraph signal in conjunction with a receiver control pulse. This telegraph signal is not further employed in the following operation.

The synchronizing pulse P received from the transmitter is superimposed by way of the contacts 31a upon the receiver testing pulses EI1 and in opposite polarity thereto, and is superimposed by way of the contact 31b upon the receiver control pulses EI2 also in opposite plurality thereto. The contacts 31a and b are closed simultaneously at the centre of the interval spacing unit before the transmission pulse P is received from the transmitter, and are opened one-quarter of a signal unit following the initiation of the transmission synchronizing pulse P. Consequently they remain closed for 75% of a signal unit.

Fig. 7g shows synchronizing pulses according to Fig. 7b and receiver control pulses according to Fig. 7e superimposed upon each other in opposite polarity for the duration of the contact 31a. The remainder of the synchronizing pulse P received from the transmitter, which occurs outside of the contact period of 31a, is represented in broken lines in Fig. 7g (and also in the following figures). In Fig. 7g the received synchronizing pulse is in phase with the receiver control pulse and the latter is just compensated, so that the phase shifter is not actuated.

In Fig. 7h it is assumed that P lags to a slight extent. The receiver control pulse is no longer rendered ineffective and causes the receiver synchronization frequency and together therewith the receiver control pulses and the distributor to be shifted in phase for such time until the receiver control pulses assume the position according to Fig. 7g.

In Fig. 7i there is indicated the extreme permissible lag of P which can still be properly compensated. If the phase of P is shifted still further to the right, the receiver control pulse is rendered ineffective by the telegraph pulse which should fall on the distributor contact 30 and the regulation of the synchronism is cut off. With the assumed duration of the received transmission pulses the greatest permissible lag accordingly amounts to 1½ signal telegraph units or bauds.

If on the other hand the transmission pulses are extended by echo effects to the duration of a signal unit, the greatest permissible lag of the pulses P amounts to merely one signal unit. It is true that with a considerable lag of this kind incorrect signals are received, but the regulation of the synchronism still operates in faultless manner, so that the transmission and receiver control pulses are again phased.

In order that considerable deviations in the phase of P from a predetermined value and the telegraphic errors thus caused do not remain unnoticed, there is provided an auxiliary contact H1, by way of which a relaxation device is actuated by the counter-connection of P and EI2. If P lags behind the contact H1, EI2 actuates a relaxation device, which actuates a relay and an indicating device.

In Fig. 7k there are shown the testing pulses P and receiver control pulses EI2 superimposed upon each other in opposite polarity during the duration of contact 31b. P and EI2 are in phase, so that the effect of P is just eliminated by EI2. If, on the other hand, P is slightly in advance as in Fig. 7l, P actuates the phase shifter. The receiver control pulses and the distributor contacts are shifted slightly in phase, so that they again assume the position according to Fig. 7k.

In Fig. 7m there is shown the extreme permissible advance of P, in the case of which the phase of the receiver control pulses is still just corrected by way of the testing contact 31b. In this connection it is assumed that P by reason of echo effects has been increased exactly to the extent of one-half of the duration of a signal unit. In the case of greater increase the advance of P may be more, but in the case of smaller increase less. Taking the most unfavourable case the maximum permissible advance amounts to approximately 75% of a signal unit.

With this considerable advance of P, as in the case of a very considerable lag, incorrect telegraph signals are recorded. Also in this

case the great advance is recorded by way of the auxiliary contact H_1 , but only if P has not been too greatly extended by echo effects. For this event there is provided a special auxiliary contact H_2 , by way of which there are actuated by P a relaxation device and an indicating device if P is too greatly in advance in relation to the receiver testing pulses.

The contacts 31a and b and also H1 and H2 are preferably so designed that they can be varied within narrow limits.

In Fig. 8 there is shown an arrangement for carrying out the method according to Fig. 7. The received transmission pulses SI act together with the receiver control pulses $EI1$ or $EI2$ on the grid of the relaxation device K_1 or K_2 . By means of the contacts $31a$ and $31b$ these pulses are applied to the grids only during the synchronizing period.

If P lags, K_1 is negatively biased by EII and is thus made non-conductive. The negative drop in potential at R_{11} is eliminated, so that the valve V_1 becomes current-transmissive and the contact a_1 is closed. The brush B of the motor M is connected with the potential O , and the motor turns the phase shifter in such fashion that the receiver pulses are shifted backwards.

The relaxation device K_1 , shortly prior to the commencement of the testing period, is positively biased by the contact $30a$ (compare Figs. 7d and 8) and thus rendered conductive. Owing to the weak negative bias of -10 v. applied to its grid by way of the resistance R_1 the relaxation device K_1 remains in the condition to which it has been brought by way of the contacts $31a$ or $30a$.

In the case of advance of P the relaxation device K_2 is positively biased by P by way of the synchronizing contact 31b and made current-transmissive. A negative voltage drop is then developed across the resistor R_{22} which blocks the valve V_2 , so that the relay is actuated and the contact a_2 is closed. By means of the contact a_2 the brush B of the motor M is connected with the potential +220 v., so that the motor rotates in the opposite direction as compared with the above example and shifts the phase of the receiver control pulses in the forward direction.

Shortly prior to the testing period the relaxation device K_2 is made non-conductive by way of the contact $30b$ (compare Figs. 7d and 8). As in the relaxation device K_1 a negative bias of -10 v. is used in order that the relaxation device K_2 may remain in the condition into which it has been brought by way of the contacts $31b$ and $30b$.

The receiver control pulses are produced in the most simple form by means of a relaxation oscillation generator, which is controlled by the synchronisation potential or a frequency derived from the same. The short receiver control pulses used for synchronizing are preferably produced by the same relaxation oscillation generator, by which the other receiver control pulses are produced, which latter serve to convert the received telegraph pulses into telegraph signals. On the other hand the long receiver control pulses must be produced by another relaxation generator, which is controlled either with the short receiver pulses or with the same synchronisation potential as the short pulses. In the latter case there must be provided a special phase shifter, by means of which the long receiver control pulses can be brought into phase with the remaining receiver control pulses.

The method according to Figs. 7 and 8 is not

limited to multiplex telegraphy. It can be employed to any other telegraph system, and more particularly also for image telegraphy.

I claim as my invention:

- 5 1. In a system for transmitting and receiving intelligence telegraphically in which unidirectional telegraph pulses and synchronizing pulses of relatively short and substantially equal duration are transmitted, said pulses first being derived from electrical telegraph signals representative of the intelligence to be transmitted and periodically interspersed with synchronizing signals, and wherein the received telegraph pulses are reconverted into electrical telegraph signals with the aid of periodic control pulses locally generated at a receiving station and synchronized with said synchronizing pulses, receiving apparatus including a relaxation device capable of assuming a first condition and a second condition characterized by the absence or presence respectively of an electron discharge in said device, means for applying the received unidirectional telegraph pulses to said device for transfer thereof from said first condition to said second condition, means for applying said locally generated control pulses to said device for transfer thereof from said second condition to said first condition for reproducing electrical telegraph signals of the same character as those from which said telegraph pulses were derived, means for applying the reproduced telegraph signals to apparatus for reproducing the transmitted intelligence, and means responsive to the received synchronizing pulses and said locally generated control pulses for developing a control effect dependent upon the phase relation between said synchronizing pulses and said control pulses and adapted to initiate synchronization of said control pulses with said synchronizing pulses.

40 2. In a system for transmitting and receiving intelligence telegraphically in which unidirectional telegraph pulses and synchronizing pulses of relatively short and substantially equal duration are transmitted, said pulses first being derived from electrical telegraph signals representative of the intelligence to be transmitted and periodically interspersed with synchronizing signals, and wherein the received telegraph pulses are reconverted into electrical telegraph signals with the aid of periodic control pulses locally generated at a receiving station and synchronized with said synchronizing pulses, receiving apparatus including a grid-controlled relaxation discharge device having a cathode, a control grid and an anode, an output resistor connected in the anode circuit of said device, means for applying a biasing potential to said grid, means for applying the received unidirectional telegraph pulses and said locally generated control pulses to said control grid in opposite polarity thereby to elevate the lower relaxation potential above the anode potential for termination of an electron discharge in said device and to lower the upper relaxation potential below said anode potential for initiation of an electron discharge in said device, thereby to produce across said output resistor telegraph signals of the same character as those from which said telegraph pulses were derived, means for coupling said output resistor to apparatus for reproducing the transmitted intelligence, means responsive to the received synchronizing pulses and said locally generated control pulses for developing a control effect adapted to initiate synchronization of said control pulses with said synchronizing pulses.

3. In a system for transmitting and receiving intelligence telegraphically in which unidirectional telegraph pulses and synchronizing pulses of relatively short and substantially equal duration are transmitted, said pulses first being derived from electrical telegraph signals representative of the intelligence to be transmitted and periodically interspersed with synchronizing signals and wherein the received telegraph pulses are reconverted into electrical telegraph signals with the aid of periodic control pulses locally generated at a receiving station and synchronized with said synchronizing pulses, receiving apparatus including a relaxation device capable of assuming a first condition and a second condition characterized by the absence or presence, respectively, of an electron discharge in said device, means for applying said locally generated control pulses and the received synchronizing pulses to said device for transfer thereof from said first condition to said second condition upon non-coincidence of said pulses, means for deriving a control signal from said device in its second condition, and means controlled by said control signal and adapted to initiate a shifting of the phase of said locally generated control pulses to produce synchronism thereof with said received synchronizing signals.
4. In a system for transmitting and receiving intelligence telegraphically in which unidirectional telegraph pulses and synchronizing pulses of relatively short and substantially equal duration are transmitted, said pulses first being derived from electrical telegraph signals representative of the intelligence to be transmitted and periodically interspersed with synchronizing signals and wherein the received telegraph pulses are reconverted into electrical telegraph signals with the aid of periodic control pulses electrically generated at a receiving station and synchronized with said synchronizing pulses, receiving apparatus including a relaxation device capable of assuming a first condition and a second condition characterized by the absence or presence, respectively, of an electron discharge in said device, means for applying said control
- 5 pulses and the received synchronizing pulses to said device for transfer thereof from said first condition to said second condition upon non-coincidence of said pulses, means for deriving a control signal from said device in its second condition, and means controlled by said control signal and adapted to initiate a shifting phase of said locally generated control pulses to produce synchronism thereof with said received synchronizing signals, and means for periodically returning said device to said first condition prior to application of said pulses thereto.
- 10 5. In a system for transmitting and receiving intelligence telegraphically in which unidirectional telegraph pulses and synchronizing pulses of relatively short and substantially equal duration are transmitted, said pulses first being derived from electrical telegraph signals representative of the intelligence to be transmitted and periodically interspersed with synchronizing signals, and wherein the received pulses are reconverted into electrical telegraph signals with the aid of periodic control pulses locally generated at a receiving station and synchronized with said synchronizing pulses, receiving apparatus including a relaxation device capable of assuming a first condition and a second condition characterized by the absence or presence, respectively, of an electron discharge in said device, a first
- 15 contact means normally open and adapted to be closed periodically for applying said locally generated control pulses and the received synchronizing pulses to said device for transfer thereof from said first condition into said second condition upon non-coincidence of said pulses, means for deriving a control signal from said device upon non-coincidence of said pulses, means controlled by said control signal and adapted to initiate a shifting of the phase of said locally generated control pulses, and a second contact
- 20 means normally open and adapted to be closed periodically for applying a predetermined potential to said device for returning the same to said first condition prior to application of said control and synchronizing pulses thereto.

ERICH HUDEC.

CERTIFICATE OF CORRECTION.

Patent No. 2,292,944.

August 11, 1942.

ERICH HUDEC.

It is hereby certified that error appears in the printed specification of the above numbered patent requiring correction as follows: Page 2, second column, line 70-71, for "phase-adjusting" read --phase-adjusted--; page 3, second column, line 62, for "80°" read --18°--; page 6, first column, line 47, after "lies" insert --between the upper relaxation potential $\bar{U}$ and--; page 7, first column, line 69-70, strike out "interval"; and second column, line 30, for "signal telegraph" read --telegraph signal--; and that the said Letters Patent should be read with this correction therein that the same may conform to the record of the case in the Patent Office.

Signed and sealed this 20th day of October, A. D. 1942.

Henry Van Arsdale,
(Seal) Acting Commissioner of Patents.
